UNITED STATES PATENT OFFICE.

OTTO ALBERT, OF MUSKEGON, MICHIGAN, ASSIGNOR TO SHAW ELECTRIC CRANE COMPANY, OF SAME PLACE.

SPRING CHOCK OR BUFFER.

SPECIFICATION forming part of Letters Patent No. 678,531, dated July 16, 1901.

Application filed March 6, 1901. Serial No. 50,074. (No model.)

To all whom it may concern:

Be it known that I, OTTO ALBERT, a citizen of the United States, residing at Muskegon, in the county of Muskegon and State of Michigan, have invented a new and useful Spring Chock or Buffer, of which the following is a specification.

This invention relates to spring chocks or buffers.

10 The object of the invention is to provide a simple and efficient construction of spring chocks or buffers.

15 The invention consists, substantially, in the construction, combination, location, and arrangement, all as will be more fully herein-after set forth, as shown in the accompanying drawings, and finally pointed out in the appended claims.

20 Referring to the accompanying drawings, and to the various views and reference-signs appearing thereon, Figure 1 is a view in side elevation, parts being broken off and parts in vertical section, of a spring chock or buffer embodying the principles of my invention. 25 Fig. 2 is a similar view showing a modified construction. Fig. 3 is a view in side elevation, showing the application of my invention to electric cranework.

30 In the drawings reference-sign A designates a block or casting in the form of a bell-crank lever pivotally mounted at the angle thereof, one arm of said lever arranged to project into position to be engaged by or to receive the impact of a wheel B or other suitable or convenient part of the truck or carriage. 35 The relative movement of the other arm of said lever is arranged to be yieldingly opposed by a spring to secure a buffer effect.

35 C designates a supporting beam or girder; 40 D, a track-rail thereon, upon which the truck or other carriage operates. The casting A is in practice pivotally connected or secured at the angle thereof, as at E, at a point adjacent to the end of the rail or other limit of 45 movement of the truck or carriage. The spring arrangement for yieldingly resisting the rocking movement of one arm of the bell-crank lever may be varied in many different ways. For instance, and in the form shown 50 in Fig. 1, a rod F is pivotally mounted or otherwise suitably connected, as at G, to sup-

porting girder or beam C or to a block or casting H, secured thereto, and is arranged to project loosely through an opening in the horizontal arm of the bell-crank lever, and a 55 spring J is interposed between said horizontal arm and a nut or block K, carried by the end of said rod. The operation of this construction is as follows: When the vertical member or arm of the bell-crank lever receives the impact of the wheel or other part of the truck or carriage, the bell-crank-shaped casting or block A is rocked about its pivot E and in a direction to effect a compression of spring J between the horizontal arm or 60 member of the bell-crank lever and the nut or block K, the compression of said spring 65 yieldingly opposing such rocking movement of the block or casting A.

70 The construction shown in Fig. 2 is similar to that above described, except that the rod F' is connected to move endwise with the rocking movement of the bell-crank-shaped block or casting A, and the spring J' is interposed between a nut or block K', carried 75 by said rod and the girder or beam C, the rod F' being provided with a head G', arranged to operate in a curved seat (indicated at L) in the horizontal arm of the bell-crank lever to accommodate for the rocking movement of 80 said arm. The operation of this form of my invention is as follows: When the upright member or arm of the bell-crank-shaped lever receives the impact of the wheel or other part of the moving frame or truck, said bell-crank lever is rocked, thereby moving rod 85 F' endwise and effecting a compression of spring J' between the block or nut K' and the supporting girder or beam C.

90 Many changes and variations in the details of construction and arrangement would readily occur to persons skilled in the art and still fall within the spirit and scope of my invention. I do not desire, therefore, to be limited or restricted to the exact construction shown and described; but,

Having now set forth the object and nature of my invention and various constructions embodying the principles thereof, what I claim as new and useful and of my own invention, and desire to secure by Letters Patent, is—

1. In a spring stop or buffer, a block or casting in the form of a bell-crank lever pivotally mounted at the angle thereof, one of the arms of said lever being arranged to project 5 into the path of the moving part to be arrested to form a stop therefor, a rod arranged to engage the other arm of said lever, and a spring carried by said rod and interposed between said arm and said rod, as and for the purpose set forth.
- 10 in one direction, as and for the purpose set forth.
- 15 2. The combination of a supporting girder or beam, a track-rail mounted thereon, a block or casting in the form of a bell-crank lever pivotally mounted at the angle thereof ad-

jacent to the end of said rail, one arm of said lever arranged to project into the path of the moving part to be arrested to form a stop therefor, a rod arranged to engage the other arm of said lever, and a spring carried by 20 said rod and interposed between said arm and said rod, as and for the purpose set forth.

In witness whereof I have hereunto set my hand, this 28th day of February, 1901, in the presence of the subscribing witnesses.

OTTO ALBERT.
